(57) **CLAIM**

The ornamental design for a rear combination lamp for an automobile, as shown and described.

DESCRIPTION

FIG. 1 is a front elevational view of a rear combination lamp for an automobile according to my new design;

FIG. 2 is a top plan view thereof;

FIG. 3 is a bottom plan view thereof;

FIG. 4 is a left side elevational view thereof; and,

FIG. 5 is a front side perspective view thereof.

The rear combination lamp is configured to be mounted to an automobile. The mounting structure and support structure of the rear combination lamp, shown ghosted within broken lines in FIGS. 1 to 5, form no part of the claimed design. In addition, the appearance of the rear and side structures of the rear combination lamp as shown ghosted within the broken lines in FIGS. 1 to 5 forms no part of the claimed design.

A second embodiment of my new design includes the mirror image of the rear combination lamp shown in FIGS. 1 to 5.
